UNITED STATES PATENT OFFICE.

EMANUEL WOODINGS, OF VERONA, PENNSYLVANIA, ASSIGNOR TO VERONA TOOL WORKS, OF VERONA, PENNSYLVANIA, A CORPORATION OF PENNSYLVANIA.

ANTICREEPING DEVICE FOR RAILWAY RAILS.

Application filed July 21, 1921. Serial No. 426,488.

To all whom it may concern:

Be it known that I, EMANUEL WOODINGS, a citizen of the United States, residing at Verona, in the county of Allegheny and 5 State of Pennsylvania, have invented a new and useful Improvement in Anticreeping Devices for Railway Rails, of which the following is a full, clear, and exact description.

10 My invention relates to anti-creeping devices for railway rails.

It has heretofore been proposed to construct two-piece anti-creepers comprising a flange-receiving member adapted to extend 15 under a rail in abutting relationship to a tie and designed to receive a locking key. Such constructions have, however, usually had one flange-receiving loop shaped to accurately engage the flange whereby the flange-receiving 20 member has been held closely against the base of the rail. This has necessitated a special abutment in order to prevent rolling the ties.

By this invention there is provided a 25 flange-receiving member so shaped that it will drop away from the rail base and provide an effective bearing surface against a tie, the cooperating key insuring a positive biting action and consequent holding of the 30 anti-creep.

Further objects will be apparent upon reading of the following description taken in connection with the accompanying drawings, in which:

35 Figure 1 shown a section of rail with one of the devices of my invention applied, the device being shown partly in section;

Figure 2 is a view similar to Figure 1, showing a modified device;

40 Figure 3 is a plan view of the device shown in Figure 2;

Figure 4 is a partial plan showing a modified form of key;

45 Figure 5 is a view similar to Figure 4 showing a further modified key;

Figure 6 is a view similar to Figure 4, showing a further modified key; and

Figure 7 is a view similar to Figure 4 showing a still further modified key.

50 Referring to the drawings, the rail 1 having the usual flange 2, is provided with a flange-receiving member 3, having a short loop 4 closely engaging the edge of the flange 2 of the rail. This member 3 passes 55 underneath the rail flange and is provided

at 5 with a larger loop which engages the top only of the flange 2 at 6. The loop 5 is provided with a transverse opening 7 to receive a tapered key 8. The opening 7 is so proportioned with regard to the edge of the rail flange and the size of the key 8 that when the key is driven into the opening one side of the key engages the edge of the rail flange at 9 and the other side of the key 8 engages the material of the member 3 at 10. 65

By reason of the construction shown, the member 3 is positively locked to the rail flange by the tremendous pressure produced upon the driving in of the gradually tapered key 8. By this means the member 3 is positively locked to the rail flange and when placed in position against the side of a tie acts to positively hold the rail against longitudinal movement. The loop 4 does not provide an accurate flange-engaging opening, 70 so that after the flange-receiving member is applied, it may drop downwardly away from the rail, thereby forming a tie abutment which engages the tie far enough from the top to prevent rolling the same. When the 75 key is driven into position, the binding action of the loop 4 is increased, and the loop 5 is moved to such a position that it engages the top only of the base flange as described.

The device of Figure 2 is quite similar to 85 that shown in Figure 1, the main distinction being that a portion 11 of the member 3 underneath the flange is rolled or otherwise flattened out so as to increase the bearing surface of the member 3 against the tie. 90 While the device of Figure 1 is satisfactory, it is in some instances advisable to increase the bearing surface against the tie, and the device of Figure 2 fulfills that requirement. As shown in Figure 3, the downwardly extending portion 11 is produced by rolling or otherwise displacing the material of the member 3, thus making the portion 11 somewhat thinner in cross section than the other portions of the member 3. 95

100 Figure 4 shows a modified form of key 12. The key shown in Figure 4 may be applied to the member 3 in the form shown in Figure 1 or in Figure 2. This key is placed in position the same as the key 8 of Figure 1, but instead of having a flat surface bearing against the edge of the flange the key 12 is provided with a special biting edge 13 which localizes the locking pressure 105 and friction between the member 3 and the 110

1 rail flange. It will be noted that the biting surface 13 on the key 12 is on the upper edge of the key as viewed in Figure 4.

5 Figure 5 shows a further modified form wherein the key 14 is provided with a plurality of biting edges 15 and 16, one being on each corner of the key in engagement with the flange.

10 The form shown in Figure 5 is the preferred form of key and has the advantage of preventing the movement of the rail with respect to the member 3 in either direction. This advantage results from the fact that the locking pressure is localized at both corners 15 of the side of the key in engagement with the flange and thereby substantially increases the locking action between the member 3 and the rail.

20 Figure 6 shows a further modification of key 17. This key has a biting surface 18 similar to the edge 13 of the key 12 shown in Figure 4 but on the opposite corner of the face of the key.

25 Figure 5 in many respects may be considered as a combination of the key shown in Figures 4 and 6.

30 Figure 7 shows a still further modification of key 19. In this case a biting surface 20 is provided along the center of the face of the key in contact with the edge of the flange.

35 Many other modifications of the key will occur to those skilled in the art and I am not to be limited to the forms shown and described, as many detail changes may be made in the device without departing from the spirit of my invention.

I claim:

40 1. An anti-creeper for rails, comprising a member passing under the rail and having loops engaging the flange on the top at both edges, said loops being shaped to permit said member to drop downwardly into inclined position, and a tapered key passing 45 through said member in engagement with the edge of the rail flange and holding said member in inclined position.

2. An anti-creeper for rails, comprising a member passing under the rail and engaging the flange on the top at both edges, and a 50 tapered key passing through said member, one edge of said key engaging the edge of the rail flange and the other edge engaging said member, said key being effective for rocking said member around one edge of the 55 base flange.

3. An anti-creeper for rails, comprising a member having a loop at one end closely engaging one flange of the rail and a loop at the other end loosely receiving the other edge of the flange and engaging the top only of the flange, and a key passing through the large loop and engaging one edge of the rail flange.

4. An anti-creeper for rails, comprising 65 a member having a loop at one end closely engaging one flange of the rail, and a loop at the other end loosely receiving the other flange and engaging the top only of the flange, and a key having a biting edge 70 engaging one edge of the rail flange and the other edge engaging said member at the large loop.

5. An anti-creeping device for rails, comprising a member passing underneath the 75 rail, said member having a loop closely fitting one edge of the rail flange, and a relatively wide portion underneath the rail, a large loop engaging the top only of the rail flange, and a tapered key having a plurality 80 of biting edges engaging the edge of the rail, said key passing through the large loop of said member.

6. In an anti-creeper for rails, a member 85 passing under the rail base and having loops engaging the rail base flange on the top at both edges, and a tapered key passing through said member and engaging the edge of the rail flange, said key having a plurality 90 of biting edges.

In testimony whereof I have hereunto set my hand.

EMANUEL WOODINGS.
